UNITED STATES PATENT OFFICE

ISIDORE SIMON, OF CHICAGO, ILLINOIS

METHOD OF MAKING SHOES, INNERSOLES, AND THE LIKE

Original application filed October 12, 1927, Serial No. 225,763. Divided and this application filed December 9, 1929. Serial No. 412,746.

This invention pertains to the method of producing devices such as shoes, and the like, for correcting foot ailments. It is known that methods of a similar character have heretofore been practiced; however, as far as applicant is aware, none of the methods heretofore employed in the manufacture of shoes have embodied the scientific principles characterizing applicant's invention as disclosed in this application.

The present application is a division of my copending application filed Oct. 12, 1927, Serial No. 225,763, which has matured into Patent No. 1,738,929, granted December 10, 1929.

An object of the present invention is to provide a method for producing shoes, and the like, which will prevent and correct abnormal distribution and abnormal direction of forces in the various parts of the human foot.

A further object of the invention is to provide a method for producing devices, particularly shoes and their innersoles, for the purpose of preventing, correcting and checking abnormal strains and stresses and abnormal distribution of force in the human foot and for treating feet subjected to other than normal forces.

Many other objects and advantages of the method herein shown and described will be obvious to those skilled in the art from the disclosure herein given.

To this end my invention consists in the various steps of a novel method for producing shoes, and the like, characterized by the construction, arrangement and combination of parts herein shown and described, and more particularly pointed out in the claims.

In the drawings employed for illustrating my improved method, and wherein like reference characters indicate like or corresponding parts:

Fig. 1 is a sectional elevation of a shoe made in accordance with the present invention;

Fig. 2 is a top plan view of an innersole adapted for a left foot, and illustrating a device characterizing one step of the improved method;

Fig. 3 is a fragmentary section taken on line 3—3 of Fig. 1 illustrating the position of a boss formed on the innersole shown in Figs. 1 and 2;

Fig. 4 is a section taken on line 4—4 of Fig. 1;

Fig. 5 is a fragmentary top plan view of the heel portion of an innersole with the top layer removed to show the position of a wedge and concavity characterizing the innersole as shown in Fig. 4;

Fig. 6 is a view in which the concavity at the heel is adapted to an ordinary shoe innersole;

Fig. 7 is a sectional view similar to Fig. 6 showing a concavity for the lateral as well as the median tubercle;

Fig. 8 is a top plan view of a last on which my improved method may be practiced;

Fig. 9 is a longitudinal section of a last with innersole applied thereto, the view being taken in the direction indicated by the arrows on line 9—9 of Fig. 8;

Fig. 10 is a transverse section of the last shown in Fig. 8 with the innersole applied thereto, and taken substantially as indicated by the line 10—10 of Fig. 8;

Fig. 11 is a section on the line 11—11 of Fig. 8 and in addition thereto showing a split innersole, the position of a wedge associated therewith, and a concavity formed in the heel of the innersole;

Fig. 12 is a detail view of the wedge shown in Figs. 4 and 5; and

Fig. 13 is a top plan view of a slightly different form of the innersole employed in practicing the present invention and illustrates a depression in the innersole for the lateral tubercle of the oscalsis as well as the median tubercle.

In carrying out the present invention, an innersole 25 (see Fig. 2) is embossed at 26 before being applied to the last, to form a counterbalance for the base of the fifth metatarsal bone of the foot, the base being a weight bearing point of the outer component part of the foot. The innersole is then split into upper part 38 and lower part 37 (see Fig. 11) from heel to shank and a leather wedge 27 inserted or a filler at the inner side of 100

the heel otherwise provided, its greatest thickness being on the medial or inner side of the foot. The purpose of this wedge or filler is to counterbalance the lateral tubercle 5 of the oscalsis located in the outer component part of the foot. Cooperative with the wedge 27 and the boss 26 is the U-shaped or semi-circular cut-away portion 28 (see Figs. 5 and 12). Cooperating therewith is the concave 10 depression 29. One of the purposes of parts 28 and 29 is to obtain a proper and perfect support at the heel, particularly on the medial side of the center line. The parts 28 and 29 receive the median tubercle of the foot. 15 This allows the wedge 27 to extend at least to the center line or further if desired in order that the proper angle and support at the heel may be obtained in aggravated and special cases. However, in the preferred embodiment, the transverse inclined plane originates at the center line. The parts 28 and 29 furthermore relieve the median tubercle of undue strain and stresses with attendant 20 tenderness and soreness so common when ordinary shoes are worn and particularly shoes of this general character. The pressure on the tip of the tubercle is obviously greatly reduced or relieved entirely and the weight is carried over a much larger surface above and 25 immediately surrounding the tubercle. It is obvious that other shapes and supports may be substituted for the wedge 27, the wedge being merely the preferred form.

The innersole 25 is embossed before being applied to the last. The embossed portion 26 is held in place by a boss filler 30 being formed of vulcanized rubber or other plastic substance. Its general shape approximates an ellipse, flat on one side and convex 30 on the other. It is cemented into the concavity formed in the under surface of the innersole due to the embossing and is then covered with canvas or other suitable material 31 and secured in place.

The innersole thus formed with mathematical precision is to be incorporated into all sizes and styles of foot wear, the boss being maintained by a vulcanizable or other plastic compound.

A new method of making shoes is thus provided in which the innersole forms a geometrical counterbalance for the weight bearing points of the outer component part of the foot. The embossed portion 26 and wedge 27 55 form the weight bearing points for the inner component part of the foot, the boss 30 and wedge 27 occurring in the innersole proper, leaving the interior side of the innersole a plain flat surface covered with canvas or other suitable material 31 interfering in no way with the channeling of the innersole, and not depending in any way upon the cork-gum 60 filler 32 used in shoe construction to support or maintain the boss 30 or the wedge 27. The

outer sole is shown at 33, the heel of the shoe at 34 and the upper at 40.

The present invention may be carried out on a last 35 with a depression as at 36 (Fig. 8) to receive the innersole with the embossed portion 26, the greatest elevation of which is located at a point on the center line of the foot opposite the shafts of the second and third metatarsal bones, respectively, at the junction of their medial and distal thirds. 75 At this point is formed one angle of an isosceles triangle, the base and head of the fifth metatarsal bone being the other two points, the base of the triangle extending from the point of the juncture mentioned above to the head of the fifth metatarsal. This formation of the depression 36 is accomplished by tooling out the last to accommodate the embossed portion 26 on the innersole. 85

The last is further formed with an elevation or boss 39 located approximately centrally of the heel portion. This elevation or boss-like formation fits into the concavity of the depression 29 in the heel seat of the 90 innersole.

The heel of the last is further shaped to receive the elevation on the innersole caused by the wedge by cutting down the wood of the last shown at 41, forming two inclined planes 41 and 42, the plane 41 with its lower point located at the medial or inner border and its highest point terminating at the center line (see Fig. 8), and the longitudinal inclined plane 42 with its lowest point located at the posterior border 43 of the heel and terminating at the junction of the heel 44 and shank 45 with the exception of an additional elevation 39 at a point located beneath the median tubercle of the oscalsis to fit into the concavity or depression 29 on the heel seat of the inner sole previously set forth. 95

It will be obvious that, if desired, a thick 100 innersole may be employed, and instead of inserting a wedge in the innersole, the outer side thereof may be cut away.

In Fig. 6 is shown a structure wherein a depression 50 at the heel for the medial 115 tubercle of the oscalsis is applied to an ordinary shoe innersole.

In Fig. 7 is shown a structure wherein a depression 46 is further provided for the lateral tubercle of the oscalsis. This form is 120 preferable in many instances, inasmuch as the depression for the lateral tubercle is equivalent in certain respects to a slightly higher wedge. Furthermore, the depression relieves undue strain on the lateral tubercle. 125 The last for making this form is further provided with an elevation or boss opposite the lateral tubercle.

In Fig. 13 is shown a top plan view of an 130 innersole illustrating the position of the de- 130

pression 46 for the lateral tubercle of the oscalsis.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A method of making shoes which consists in permanently embossing the innersole opposite the metatarsal bones, providing a greater thickness on the inner side of the heel, forming a depression in the floor of the innersole at the heel for receiving the median tubercle of the oscalsis, applying the inner sole to a last, and completing the operations of making a shoe.

2. A method of making shoes which consists in forming a raised arcuate portion in the innersole opposite the second and third metatarsal bones, inserting a filler in the under side of the innersole to permanently maintain said raised portion, splitting the innersole at its inner edge from the heel toward the shank and inserting a wedge on the inner side of the heel with its greatest thickness at said inner edge, forming a depression in the floor of the innersole at the heel portion at a predetermined point, applying the innersole to a last, and completing the operations of making a shoe.

3. A method of making shoes which comprises forming a raised portion in the upper surface of the innersole opposite the metatarsal bones, inserting a filler on the under surface to maintain said raised portion, covering the filler and part of the under surface of the innersole with a sheet of material and securing same in place, splitting the innersole at the rear portion thereof from the heel toward the shank, inserting a filler at the inner side of the heel, securing the filler and split portions together, forming a depression in the upper surface of the innersole in the heel portion to receive the median tubercle of the oscalsis, placing the innersole on the last, and completing the operations of making a shoe.

4. A method of making shoes which comprises forming a raised portion in the upper surface of the innersole opposite the metatarsal bones, inserting a filler on the under surface to maintain said raised portion, covering the filler and part of the under surface of the innersole with a sheet of material and securing same in place, splitting the innersole at the rear portion thereof from the heel toward the shank, inserting a filler at the inner side of the heel, securing the filler and split portions together, forming a depression in the upper surface of the innersole in the

heel portion to receive the median tubercle of the oscalsis, forming a second depression in the upper surface of the innersole in the heel portion to receive the lateral tubercle of the oscalsis, placing the innersole on the last, and completing the operations of making a
